SWITCH

James B. Forker, Jr., Cleveland, Ohio, assignor
by mesne assignments, to The Cleveland Crane
and Engineering Company, Wickliffe, Ohio, a
corporation of Ohio

Application October 2, 1934, Serial No. 746,546

11 Claims. (Cl. 104—102)

This invention relates to a sliding switch for overhead conveyor systems and has among its purposes the simplification of the suspension of such a switch, with resulting reduction in the weight and expense of the supporting steel work necessary. A further beneficial result from such simplification is that the switch can be installed expeditiously, and in particular, levelled up quickly and accurately. The switch of this invention is adapted to be included in an overhead track system with very little special supporting work and in some situations with no support in addition to that for the general track suspension.

Another advantage resulting from the method of support is that it enables a plurality of these switches to be closely spaced where necessary to serve several parallel tracks.

Among other purposes of the invention is the introduction of a sliding switch made in the factory as a completed unit to be installed in the field with a minimum of cutting and fitting of adjacent track sections and no bending of such sections even in situations where the switch makes large changes in direction.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In the accompanying drawings Fig. 1 is a plan view from above, showing the switch assembly and its connections to a conveyor system; Fig. 1A is a detail from Fig. 1 on the line 1A—1A; Fig. 2 is a corresponding view showing the switch at the other end of its throw; Fig. 3 is a side elevation in the direction of the arrows 3—3 Fig. 1; Fig. 4 is an end elevation in the direction indicated by the arrows 4—4, Fig. 1; and Fig. 5 is a diagrammatic plan of various applications of the switch in a standardized steel frame factory building. Fig. 5 is upside down to Figs. 1 and 2. In Figs. 1 and 2 the rail webs and the hanger fittings or cleats are omitted to simplify the drawings. The features omitted from Figs. 1 and 2 are shown in Figs. 3 and 4. Some of the rail hangers shown in Figs. 1 and 2 are omitted from Figs. 3 and 4 for simplicity.

As best seen in Figs. 1 and 2, the switch comprises a frame and a carriage movable thereon. The frame comprises four members, 1, 2, 3 and 4,

preferably made up of structural shapes such as angle bars welded together. In this frame the end members are designated as 1 and 2 and the side members as 3 and 4. As a matter of convenience the description and claims will be made with reference to a trolley moving upward of the sheet, Figs. 1 and 2, that is, entering the switch at the side 3. Consequently the side 3 will be referred to in the description and claims as the "near" or "entering" side, the end 1 will be termed the right end, and so on. It will be understood that these designations are merely arbitrary and that cars may move in either direction through the switch. The flanges of the side bars 4 serve as rails for the wheels 5 of the carriage.

The carriage is also preferably built of structural shapes, such as angles welded into a rectangular frame, and runs on its tracks through a distance which is limited by the ends 1 and 2 of the frame. The preferred carriage construction here shown comprises side bars 6 through which the axles 7 pass, the wheels 5 being on the outside of the side bars. A plate 8 is welded beneath these bars and rail hangers 9, 9, and 10, 10 are in turn welded or otherwise secured beneath the carriage. The rail hangers 9, 9 suspend a rail section 11 curved to the right and the rail hangers 10, 10 suspend a straight rail section 12 transverse to the switch, both of which will be described in greater detail hereafter. When the movable curved section 11 is in operative position, Fig. 1, it is continued by a fixed curved rail section 11A, suspended from the side 4 of the switch frame by hangers 9A. The sections 9 and 9A together make a 90° curve. Trolleys enter the switch only by the one track 13, and leave it by the track 14 at right angles when the switch is thrown to the left, Fig. 1, or by the opposing track 15 when the switch is thrown to the right, Fig. 2.

The carriage is traversed by any suitable means such as chains 20 running over sheaves 21. Latches 22 hold the carriage at either end of its run. Other attachments upon the carriage are clips 25 which underrun the edges of the frame flanges 3, 4 to keep the carriage from lifting, and limit stops 26 on the end flanges 1, 2.

Safety features include means to keep trolleys from running off open ends of the tracks 13, 14 and 15 and also to guard the open ends of the switch rails 11 and 12 in the event of the switch being thrown with a trolley on either movable rail, as may happen. In the preferred construction herein illustrated and described, the safety

arrangements are all related to a controlling minimum trolley width, as shown in Fig. 3, whereby some pairs of rail ends guard one another without requiring special parts. Special 5 guards are necessary for others, but the size and disposition of these special guards are also influenced by trolley width, the principal effect being to reduce the size of guards necessary, 10 which aids somewhat in lowering the weight of the entire switch assembly. To illustrate this feature a trolley is shown in Fig. 3 to the same scale as the track. This trolley is the same as shown in Fig. 1 of my co-pending application Serial No. 681,337, filed July 20, 1933, but with 15 the addition of safety lugs L.

The ends of rail 12 are protected in the position of Figs. 1 and 3 by plates 16, 16 attached to the under side of the main frame sides 3, 4 and coming down far enough to block the upper part 20 of the trolley. At the same time a plate 17, attached under the switch carriage as shown in Fig. 1A, protects the track 15. When the switch is thrown to the right, Fig. 2, the "entering" end of track section 11 comes opposite a plate 16A, similar 25 to plates 16, while the "leaving" end of 11 and the end of 11A protect one another because so placed that when the switch is in the position shown in Fig. 2 a lug L of a trolley on 11 will strike the exposed end of 11A before the 30 trolley can run off. Similarly a trolley on 11A is prevented from running off because one of its lugs L will strike the point of 11. See upper right corner of Fig. 2. All rails are protected when the switch carriage is in intermediate 35 positions by reason of the fact that before the carriage has moved a rail width in either direction the path of some part of the trolley will be blocked by an end of a plate 16, 16A or 17.

The entire switch assembly is supported at 40 three points, 30, 31 and 32, each of which is shown in Figs. 1 and 2 as a horizontal section through a hanger rod. The details of preferred hangers are seen in Figs. 3 and 4, but are omitted from Fig. 1 to simplify the figure. These hanger rods 45 constitute the sole support for the switch frame. They are joined thereto by appropriate suspension fittings such as 35, 36 and 37, respectively, the details of which are subject to a considerable range of variation according to special requirements. For example, in Fig. 4, the "entering" 50 rail 13 and the "leaving" rail 14 are shown as of the same section as the switch rails 11 and 12, whereas the other "leaving" rail 15, as shown as a beam with the web and top flanges of I-beam section and having its lower flanges of 55 rail section. This is only one example, other variations may be used as indicated by any particular situation. The tracks 13, 14 and 15 which are served by the switch are not a part of the 60 switch. They are straight rails cut square across the ends. The ends of these tracks adjacent the switch are suspended by the same hangers 30, 31 and 32 and fittings 35, 36 and 37 which suspend the switch. Thus each of the three points of 65 switch support also holds the adjacent end of its corresponding incoming or outgoing rail. Both ends of the rail 12 are cut square across to match the ends of 13 and 15 and the length of 12 is such as to leave only the necessary clearance for switch throw. 70

As previously mentioned, the rails 11 and 11A together make a 90° curve which connects the tracks 13 and 14 when the switch is in the position of Fig. 1 and is inoperative in the position 75 of Fig. 2. A satisfactory method of manufacture

to insure accuracy is to build the switch in the position of Fig. 1, using a single properly bent length of rail for the entire curve from 30 to 31. This single length is welded or otherwise fastened to the hangers 9 and 9A, all accurately 5 positioned. In quantity production the cuts 38 may be made before the rail is welded on, using a jig to guide the cut. Thus there are no difficulties of alignment and registry of ends between the sections 11 and 33. Close calculations and 10 trial-and-error fitting are alike avoided.

The curve 11, 11A is convex toward the suspension point 32, with the result that live loads on the curve 11, 11A are all carried within the triangular area established by the points 30, 31, 15 32 and are suspended only at these three points. Obviously the hangers at points 30, 31 and 32 also suspend the dead weight of the switch.

Live loads on rail 12 are supported by the points 30 and 32 when the switch carriage is in the position of Fig. 2. A special situation arises when the switch carriage is moved to the position of Fig. 1 with a live load on the rail 12. In this instance so much of the load to the left of the line between 30 and 32 as is not counterbalanced 20 by the weight of switch structure to the right of such line causes an upward movement at the point suspended by the hanger 31. This is resisted largely by the rail 14, inasmuch as the element 31 will ordinarily be a rod having little 25 strength in compression.

For the reason that all rail elements of the switch are so manufactured that all three track ends served by the switch are made by square 30 end cuts of straight sections, no rail bending and 35 no diagonal cutting is required in erecting the system and the only requirement which the installation of this switch imposes upon the erector is that he must cut his rails accurately to length. Then the switch and the tracks to it can be 40 levelled up by adjustments at only three points.

In order that the switch may be levelled up an adjustment is provided for each of the three suspension elements 30, 31 and 32. In the form 45 shown herein, each of these elements is brought into the horizontally disposed upper part of a coupling such as 35, 36 or 37 and held there between nuts on the threaded lower portion of the suspension element. Taking the coupling 35, Fig. 4, as typical, the suspension element is the 50 rod 30. The threaded lower end of this rod passes through a hole (not shown) in the horizontal portion 35A of the coupling 35. The coupling is adjusted in height by the lower nut 30A and locked by the upper nut 30B. Any other 55 suitable adjusting mechanism might be used.

Reference has been made to the utility of the present switch in tramrail systems within steel frame buildings. On account of the fact that no curvature need be put in the incoming and 60 outgoing sections, every rail element served by the switch requires nothing beyond end suspension as a beam, and this end suspension is common to one of the points of suspension of the switch. 65

Fig. 5 illustrates several possibilities of economy in installation, all resulting from the three-point support. This figure shows in diagrammatic plan one complete bay and parts of others in a steel frame building of the partly prefabricated type. The elements 40 and 41 represent transverse trusses, longitudinal superstructure spanning the distance between successive trusses is represented by 42 and 43, a continuation of 43 is shown at 44, and 45 indicates additional super- 70 75 75

structure parallel to 43 necessary on account of the special installation. The switches shown in Fig. 5 are fixed in the opposite direction to Figs. 1 and 2. Part of the 40-41 bay is to be used for closely placed tracks 14A to 14E inclusive, such as might be used for storage or classification purposes. All of these are served by the incoming track 13 which is assumed to be of the shallow rail as shown in Fig. 4, which is not strong enough to carry rods over long spans but must be suspended in any usual manner at fairly frequent intervals from the superstructure 45, 43. Each of the tracks 14A to 14E inclusive is served by a switch of the present invention, these switches being indicated A, B, C, D and E, respectively. Each switch except E is suspended by its respective points 30 and 32 from the superstructure 43, while the point 31 is suspended from the additional superstructure 45. The five switches are all placed side-by-side with no waste room between. Each two adjacent switches have the suspension elements 30, 32 in common, this being accomplished by bringing the web of the frame member 3 of switch E, for example, against the web of the frame member 4 of switch D and embracing both webs between the jaws of the coupling 35.

In Fig. 5 switch A is shown as thrown to the position of Fig. 2, and B is in the position of Fig. 1, so that trolleys run straight through A and are turned onto track 14B.

The additional superstructure 45 is required for the suspension of the points 31 of all switches except E. Only one line of superstructure is necessary because each switch suspension 31A to 31D also suspends the end of the adjacent track rail, which would not be possible if some of the curvature which my improved switch accomplishes by 11, 11A had to be included in the track rail.

The switch E also illustrates another saving to which three point suspension gives rise; namely, that my switch installed to make a turn to a track under one of the building trusses requires absolutely no superstructure beyond that which is required anyhow for the track. If the switches A, B, C, D were omitted the superstructure 43 would still be required to hold up the rail 13, and the truss 41 would still be a necessary part of the building even if there were no tramrail system. But the suspension 30 is from 43, the suspensions 32E and 31E are from 41, and that is all. It is thus apparent that the additional superstructure 45 is not required for switch E and performs no function in respect thereto. On the other hand if any part of the change of direction made by E had to be included in the track 14E a suspension would be needed from 41 to 14E at the end of the tangent and another at the end of the curve, but the suspension to 14E at the end of the curve would have to be out from under 41 and would consequently necessitate some superstructure.

Further considering switches A, B, C and D, if the entire curvature were not included in the switch, a second line of superstructure parallel to 45 would be required, for the same reasons that apply with respect to switch E and track 14E. Although it is true that the support of the "yard" of Fig. 5 using only one additional frame is predicated upon using rail of sufficient strength to bridge the distance from 40 to 44, (such as the deep webbed rail 15, Fig. 4) so far as the immediate support of the switches are concerned, overhead support is required only for the three suspension points.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In an overhead conveyor system a plurality of switches, each adapted to give either a straight run or a turn, said switches each having three supports in right triangular arrangement, a common means for carrying in alignment the supports defining one leg of the triangle of each switch, each support in such alignment and not at the ends thereof being common to two switches, said aligned supports being in the line of the straight track relation of said switches, the third support of each switch being carried by means parallel to said above-named "common means", said third support in each switch supporting an end of the turn.

2. In combination in an overhead conveyor system, tracks including rails having tread flanges, switches to connect said tracks selectively, said switches including rail sections movable a definite distance in translation to and from positions where said sections abut track rails, and a trolley movable on the tracks of said system, the transverse width of the trolley in the plane of said tread flanges being greater than said distance of translatory movement.

3. In an overhead tramrail conveyor system of the class described, the combination of rails having tread flanges, a trolley comprising wheels and a yoke suspended therefrom, side extension lugs on said yoke, said lugs being aligned in height with the rail tread flanges whereon said wheels run, whereby to stop said trolley against rail ends sidewardly displaced but within reach of said lugs, the side reach of said lugs spanning the designed displacement of rail ends.

4. In combination in an overhead conveyor system, tracks, switches to connect said tracks selectively, said switches including rail sections movable a definite distance in translation to and from positions where said sections abut track rails end to end, and a trolley to run in said system, said trolley including a yoke having side elements adapted when the trolley is moving on one switch rail section or track to the switch to strike an opposed but discontinuous track or rail section, respectively, the reach of said side elements spanning the said definite distance.

5. In an overhead conveyor switch unit, a frame and a carriage movable in translation on said frame, a straight rail and a curved rail carried by said carriage, said straight rail being disposed at right angles to the direction of movement of said carriage and adapted when the carriage is at one end of its travel to connect two aligned track ends, said curved rail constituting part of a curve, a stationary curved rail section rigidly and permanently fixed to said frame and adapted to act as a support for said frame and constituting the remainder of the total change of direction, said movable curved rail section being adapted to connect one of said track ends with the stationary curved section when the carriage is at the other end of its travel, and means for supporting said switch, said means consisting of a suspension at each point of juncture between a rail of the switch unit and a track rail.

6. In an overhead conveyor system a plurality of switches, each adapted to give either a straight

run or a turn, means for supporting each of said switches consisting of three supports in triangular arrangement, a common means for carrying in alignment the supports defining one leg of the triangle of each switch, each support in such alignment and not at the ends thereof being common to two switches, said aligned supports being in the line of the straight track relation of said switches, the third support of each switch being carried by means parallel to said above-named "common means."

7. In an overhead conveyor system a plurality of switches, each adapted to give either a straight run or a turn, said switches each having three supports in triangular arrangement, a common means for carrying in alignment the supports defining one leg of the triangle of each switch, each support in such alignment and not at the ends thereof being common to two switches, said aligned supports being in the line of the straight track relation of said switches, the third support of each switch being carried by means parallel to said above-named "common means".

8. A transfer type switch unit for an overhead tramrail system adapted to be interposed between and connect or serve straight sections of track, said switch unit comprising a frame, a member movably supported by said frame, a curved rail section rigidly and permanently fixed to said frame and adapted to act as a support for said frame, a plurality of rail sections fixed to said movable member, one of said last mentioned rail sections being a curved rail section adapted to be aligned with the first mentioned curved rail section for one position of said movable member, and means for supporting said switch, said means consisting of suspensions located in line with the straight sections of track connected or served by said switch unit.

9. A transfer type switch unit for an overhead tramrail system adapted to be interposed between and connect or serve straight sections of track, said switch unit comprising a frame, a

member movably supported by said frame, a curved rail section rigidly and permanently fixed to said frame and adapted to act as a support for said frame, a plurality of rail sections fixed to said movable member, one of said last mentioned rail sections being a curved rail section adapted to be aligned with the first mentioned curved rail section at one position of said movable member and form therewith a 90° curve, and means for supporting said frame, said means consisting of suspensions located in line with the straight sections of track connected or served by said switch unit.

10. A transfer type switch unit for an overhead tramrail system adapted to be interposed between and connect or serve sections of track, said switch unit comprising a frame adapted to be suspended from a suitable support, a member movably supported by said frame, a curved rail section rigidly and permanently fixed to said frame and adapted to act as a support for said frame, and a second curved rail section fixed to said movable member and adapted to be aligned with the first mentioned curved rail section for one position of said movable member.

11. A transfer type switch unit for an overhead tramrail system adapted to be supported between and connect or serve straight sections of track, said switch unit comprising a frame adapted to be suspended from a suitable support, a member movably supported by said frame, a curved rail section rigidly and permanently fixed to said frame and adapted to act as a support for said frame, and a second curved rail section fixed to said movable member and adapted to be aligned with the first mentioned curved rail section for one position of said movable member, the end of the first mentioned curved rail section remote from said second curved rail section lying in a plane normal to the straight section of track adjacent thereto.

JAMES B. FORKER, JR.
